TURNBUCKLE WRENCH

Victor Price, Akron, Ohio

Application February 1, 1944, Serial No. 520,662

1 Claim. (Cl. 81—90)

My invention relates to improvements in ratchet-type wrenches for use in turning turnbuckles, the principal object in view being to provide a simply constructed, inexpensive and easily applied wrench for use in connection with turnbuckles of the type having a center tool opening therein.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of my improved wrench, in its preferred embodiment.

Figure 2 is a view in edge elevation.

Figure 3 is a similar view partly in longitudinal section, taken on the line 3—3 of Figure 1.

Figure 4 is a fragmentary view in side elevation of the handle.

Figure 5 is a view in side elevation of the ratchet band, and

Figure 6 is a view in elevation of said band.

Referring to the drawings by numerals, my improved wrench, as illustrated, comprises a ratchet wheel 1 formed in mating half-sections 2 designed to fit around a turnbuckle 3, it being understood that such wheels will be provided in different sizes for different sizes of turnbuckles. A pair of radial, diametrically opposite pins 4 are provided in said sections, respectively, in the centers thereof to extend inwardly therefrom and fit in the usual transverse opening, or bore, 5 provided in such turnbuckles for the insertion of a tool therein. A pair of flat links 6 upon opposite sides of the wheel 1, respectively, with pins 7 extending therethrough and through the sections 2 hingedly connect the sections 2 together at one side of the axis of the wheel for opening and closing of the sections to apply and detach the wheel. On the opposite side of said axis, a pair of spring catches 8 secured to one section 2, as at 9, upon opposite sides thereof, are adapted for snap action engagement with a pair of depressions, as at 10, in the opposite sides of the other section 2 to lock said sections closed.

For turning the wheel 1, a resilient, ratchet band 11, and a flat bar-like handle 12 are provided, the band being designed to fit loosely around the wheel 1 for rotation about the same. The handle 12 is provided with a concave, widened end 13 forming a pair of edge ears 14, 15 at opposite corners of said end to one of

which, for instance 15, one end of the band 11 is pivoted by means of a pair of hinge lugs 16 formed on said end and inserted in a concave socket 17 in the handle 12, said lugs 16 straddling a lug 18 on the handle and being secured to the lug 18 by a pintle 19. The other end of the band 11 is provided with a single ratchet tooth 20 arranged to be engaged by the other ear 14 when the handle 12 is swung in a direction to rotate the wheel, and whereby said tooth is held in the teeth of the wheel 1 during operation of the wrench to turn a turnbuckle. The ear 15 forms a stop behind the pivot of the band 11 coacting with the band when the handle 12 is swung reversely to thereby limit such swinging thereof relative to the band 11 so that the latter may be rotated around the wheel 1 to advance the ratchet tooth 20 over the teeth of said wheel.

Inwardly projecting edge lugs 21 are provided on the band 11, on one edge thereof, to prevent the same from slipping sidewise of the wheel 1, or downwardly, if the turnbuckle is arranged in vertical position.

In the use and operation of the described wrench, the wheel 1 is first applied, in the manner already set forth, with the ratchet band detached therefrom and the band is then applied sidewise over the wheel. As will be clear, swinging of the handle in one direction, clockwise as viewed in Figure 1, will engage the ear 14 with the ratchet tooth 20 to press the same into a tooth of the wheel 1 and then rotate or revolve the band 11, thus imparting similar movement to the wheel 1 to turn the turnbuckle 3. Swinging of the handle 12 in the opposite direction will rotate or revolve the band 11 about the wheel 1 to advance the ratchet tooth 20 into another tooth of said wheel.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

A wrench for use on turnbuckles of the type having a transverse tool-receiving opening therein comprising a ratchet wheel including a pair of mating half-sections adapted to be opposed upon opposite sides of the turnbuckle in surrounding relation thereto, means to secure said sections together against relative separation, key pins in said sections for insertion in said open-

ing to lock the sections to the turnbuckle, a handle, and a resilient band of annular form partly surrounding the wheel with one end connected to said handle and the other end thereof provided with a ratchet tooth for engaging the teeth of the wheel, said band being removable edgewise from said wheel, said means comprising hinges on one side of the axis of the wheel, and latches on the other side of said axis, said toothed

5 end of the band being interposed between one end of the handle and said wheel, and the connected end of the band being hinged to said end of the handle whereby said handle may be swung in one direction to retain the toothed end of the band engaged with the teeth of said wheel and simultaneously rotate the wheel.

VICTOR PRICE.
